UNITED STATES PATENT OFFICE.

WILLIAM A. FINLAYSON, OF DETROIT, MICHIGAN.

RADIATOR.

1,411,334.

Specification of Letters Patent. Patented Apr. 4, 1922.

Application filed July 30, 1920. Serial No. 400,235.

To all whom it may concern:

Be it known that I, WILLIAM A. FINLAYSON, a citizen of the United States of America, residing at Detroit, in the county of Wayne and State of Michigan, have invented certain new and useful Improvements in Radiators, of which the following is a specification, reference being had therein to the accompanying drawings.

10 The invention relates to radiators designed to lower the temperature of the cooling water for an engine by means of air, and is particularly applicable to automobile radiators. One object of the invention is to 15 provide a simple construction comprising tubes adapted for the passage of air and water arranged adjacent to each other for a substantial distance. Another object is the provision of a chamber in the radiator 20 for receiving the air after passing through the water space. The invention has for further objects the novel arrangements and combinations of parts as more fully hereinafter set forth.

25 In the drawings:

Figure 1 is a diagrammatic view of a radiator embodying my invention, in front elevation partly broken away;

Figure 2 is a similar view in side elevation partly broken away;

Figure 3 is a front elevation partly in section of a portion of the radiator core;

Figure 4 is a side elevation of a modified construction.

30 1 is the core of the radiator to which is connected the upper and lower water chambers 2 and 3 respectively, which are connected by the series of vertical tubes 4. 5 is the water inlet into the upper chamber 2 and 6 the water outlet from the lower chamber 3. 7 is the upper or cap portion of the radiator casing which is suitably secured to the upper chamber 2 and forms therewith the upper chamber 8 for containing air. 9 is the 40 lower or base portion of the radiator casing which is suitably secured to the radiator casing which is suitably secured to the chamber 3 and forms therewith, the lower air chamber 10. 11 is a series of vertical tubes 45 connecting the upper and lower air chambers, these tubes extending through the water tubes 4 and in parallelism therewith. 50 The front of the lower air chamber 10 is open and the bottom wall 12 of this air

chamber is curved rearwardly and upwardly 55 to change the direction of flow of the air entering the air chamber and passing into the tubes 11 from horizontal to vertical. With this arrangement, the air is forced into the air tubes when the automobile is moving forward.

13 is an air outlet connection from the upper air chamber 8 having the outlet opening 13' adapted to be connected to the interior of an automobile body or sedan and the by-pass opening 13² for providing for circulation of the air through the radiator when the outlet opening is closed. 14 is a suitable valve adapted to close either of these openings. The by-pass shown in Fig. 2 is also in the outlet shown in Figure 4 although the by-pass in the latter instance is not shown.

If the automobile is at rest, the radiator may be kept warm by means of the heater 15 having an outlet, hot air connection 16 extending up through a suitable aperture 17 in the bottom wall 12 of the lower air chamber. This heater may be secured to the radiator as by being engaged with the hook 18 upon the lower front side of the radiator.

The upper and lower water chambers 2 and 3 are secured to each other as by means of the rods 19 which engage laterally extending flanges upon the chambers. The bottom and top, or the headers, of the respective air chambers 2 and 3 are provided with the bosses 20 which have the conical seat portions 21 for engaging the conical ends 22 of the tubes 4. By securing these headers to each other it will be seen that the tubes 4 will be firmly secured in place and that the joints at the ends of these tubes will be water-tight. The air tubes 11 are also preferably secured to the core 1, and as shown in the upper and lower sides, or the outer headers, of the chambers 2 and 3 respectively, are provided with cup-shaped bosses 23, the bases of which are apertured for the passage of the ends of the tubes 11 therethrough. 24 are conical bearing portions upon the bases of these bosses which are engaged by the conical ends 25 of the bushings 26 threadedly engaging in the cup-shaped bosses, the arrangement being such that upon inward movement of the bushings their inner conical ends are laterally forced into firm engagement with the ends of the

tubes. These bushings are preferably formed with hexagonal heads 27 for engagement by a wrench.

28 are suitable heat radiating fins extending across and around the tubes 4.

From the above description it will be readily seen that I have provided a simple radiator construction which can be readily manufactured and furthermore in which the 10 air passing to the upper chamber is in contact with the water space of the radiator for a substantial distance so as to absorb an appreciable amount of heat. Also this heated air can be utilized if desired to heat 15 the interior of an automobile body or sedan.

As shown in Figure 4, the front of the air receiving chamber 29 is closed and its bottom is open and the lower heat radiating fin 30 extending transversely of the series of 20 tubes has a rearward extension 31 which is curved downwardly and forwardly beneath the air receiving chamber 29 and terminates at its front wall. This arrangement is such that a portion of the cooling air in passing 25 through the radiator and around the tubes, is directed into the air receiving chamber by the extension of the air cooling fin upon movement of the motor vehicle carrying the radiator. Another feature as disclosed in 30 this figure, is the device for filling the radiator water chambers and water tubes with water. This member 31 has the portion 32 which is adapted to extend into the filler neck 33 of the radiator. The portion 32 for the water curves downwardly and rearwardly to lie adjacent to the rear face of the 35 upper water chamber 34, this rear face having an aperture therethrough communicating with the passageway. The device also 40 has the rearwardly and downwardly extending tubular portion 35 which is adapted to be connected to the water jacket of the engine and by means of which the hot water from the engine is conducted into the upper 45 water chamber 34.

What I claim as my invention is:

1. In a radiator, the combination with a space for containing water, of a series of vertical tubes for the passage of air extending 50 through said water space and an air chamber at the upper end of said tubes having a valve controlled outlet.

2. In a radiator, the combination with a series of vertical tubes for the passage of water, of a series of vertical tubes for the 55 passage of air, the tubes of one series surrounding the tubes of the other series and an air chamber at the upper ends of said second mentioned tubes, said air chamber 60 having a valve controlled outlet.

3. In a radiator, the combination with upper and lower chambers for air, of intermediate upper and lower chambers for water, vertical tubes connecting said air 65 chambers, vertical tubes surrounding said

first-mentioned tubes and connecting said water chambers, a valve controlled outlet in said upper air chamber and a curved wall in said lower air chamber for changing the flow of air from horizontal to vertical directions. 70

4. In a radiator, the combination with a water space, of a vertical passageway for air through said water space provided with an outlet opening and a by-pass opening, and a valve for alternatively closing either opening. 75

5. In a radiator, the combination with hollow upper and lower water chambers, of tubes connecting said chambers and having 80 their ends abutting the inner walls thereof, other means for clamping said walls upon the ends of the tubes, tubes extending through said first mentioned tubes and through said water chambers, and means upon the outer walls of said chambers for 85 clamping the ends of said last mentioned tubes. 90

6. In a radiator, the combination with hollow upper and lower water chambers, of tubes connecting said chambers and having 90 their ends abutting the inner walls thereof, means for clamping said walls upon the ends of the tubes, and other tubes extending through said first mentioned tubes and through said water chambers. 95

7. In a radiator, the combination with upper and lower water chambers, of tubes connecting said water chambers, air tubes surrounding said first mentioned tubes and passing through said water chambers, and transversely extending fins upon said tubes, one of said fins provided with means for directing air into the lower ends of said air tubes. 100

8. In a radiator, the combination with an upper air chamber and an upper water chamber therebeneath, of means for conducting water into said water chamber, said means having a passageway extending into the filler neck of the radiator and extending rearwardly and downwardly to lie adjacent 105 to the rear face of said water chamber and communicating therewith.

9. In a radiator the combination with an upper air chamber and upper water chamber therebeneath, of means for directing 115 water into said water chamber, comprising a passageway leading from the filler neck of the radiator, downwardly and rearwardly to lie adjacent to the rear face of said water chamber, said passageway communicating 120 with said water chamber, and a second passageway adapted to conduct water from an engine water jacket, said second passageway communicating with said water chamber through its rear face. 125

10. In a radiator, the combination with hollow upper and lower water chambers, of tubes connecting said chambers and having 130 their ends abutting the inner walls thereof, means for clamping said inner walls upon

the ends of said tubes, cup shaped bosses upon the outer walls of said water chambers having apertured bases and conical bearing portions adjacent thereto, tubes extending through said first-mentioned tubes and into said cup shaped bosses, and bushings threadedly engaging in said cup shaped bosses and having conical ends cooperating with the conical bearing portions upon said 10 cup shaped bosses for firmly engaging said tubes.

11. In a radiator, the combination with hollow upper and lower water chambers, said upper chamber having conical seat 15 portions on its lower wall and apertured cup

shaped bosses on its upper wall, said lower chamber having conical seat portions on its upper wall and apertured cup shaped bosses on its lower wall, of tubes connecting said chambers and having conical ends engaging 20 said conical seat portions, tubes extending through said first-mentioned tubes and into said cup shaped bosses, bushings threadedly engaging in said cup shaped bosses and provided with conical ends for engaging said 25 second mentioned tubes, and means for securing said upper and lower chambers in fixed relation to each other.

In testimony whereof I affix my signature.

WILLIAM A. FINLAYSON.
